PARAFFINING MACHINE

Karl E. Garling, Newark, N. J., assignor to Soda
Straw Manufacturing Corporation, Newark,
N. J., a corporation of New Jersey

Application March 25, 1931, Serial No. 525,167

5 Claims. (Cl. 91—42)

The machine herein disclosed is more particularly employed in the manufacture of sip-straws, or straws made from paper strips spirally rolled to form slender tubes. These tubes are cut to length and are employed very largely in drinking soda dispensing emporiums.

Among the principal objects which the present invention has in view are: To treat the sip-straws to a bath in very highly treated paraffine; to secure thereby the maximum penetration of the paraffine into and about the sip-straws; to subsequently remove from the sip-straws all surplus paraffine; to speed up the operation and to economize in the use of the paraffine.

15

Drawings

Figure 1 is a vertical section of a paraffining machine when constructed and arranged in accordance with the present invention, the parts 20 being shown in their opened or out of service position.

Figure 2 is a similar view showing the first steps followed during the operation.

Figure 3 is a cross section of the machine shown 25 as on the line 3—3 in Figure 2.

Description

The herein disclosed apparatus consists principally of three principal mechanisms. The one 30 is the double boiler 8, another the container 9, and the third the motor 28. In the boiler 8 is placed a charge of paraffine indicated by the letter X in Figures 1 and 2. The paraffine is melted by heated water introduced through the 35 pipe 11 to sections 12 and 13 of the boiler 8. The upper section 12 of the boiler 8 is removed from the lower section 13 to form a heated centrifuging chamber above the paraffine into which the container 9 is received to be there revolved rapidly by the motor 28 through the means of the 40 shaft 14, for expelling, or throwing off surplus paraffine lengthwise of the straws, so that no paraffine remains attached to or lodged within the straws but that which has permeated the body 45 of the product. Each container is offset from the center of rotation, so as to insure centrifugal action the entire length of the product in amount greater than the adhesion or viscosity tension of the paraffin. The upper section 12 and the lower section 13 are connected through 50 pipes 15.

A cover 16 may be lowered to close the top opening 17 of the container 9, thus preventing any escape of heat from the container and the 55 product being treated. By this arrangement the

heat that is held in the double boiler 8, is all that is necessary to insure the perfect action of infiltration of the paraffine throughout the product being treated.

It will be understood that the circulation of 5 heated water is maintained through the pipes 11, 15 and 18 and the nipples, connecting the same with the sections 12 and 13. A heater, not shown herein, is used for maintaining the heat at the proper degree and by using a double boiler as 10 shown, any burning of the paraffine is avoided.

The product heretofore referred to which is handled in the present machine is sip-straws. These straws are gathered and placed in wire baskets 19 as shown best in Figure 3 of the drawings. The container 9 is arranged to form open pockets or receptacles 20 in which the baskets 19 are placed, the straws being disposed radially of the container, so that the surplus paraffine is discharged therefrom lengthwise thereof. As 15 may be seen more especially in Figure 3 of the drawings, the pockets or compartments 20 provide a greater radial length than width, and baskets 19 are constructed to substantially fit within these compartments so that the straws 20 contained therein cannot possibly assume any other position than a substantially radial position with respect to the container. This arrangement results in the paraffine being caused to 25 unfailingly pass through each straw as well as 30 through the crevices existing between the several straws, and thus paraffine is, by the centrifugal action, applied throughout the length of the straws, particularly on the inside thereof, in an even 35 condition and without any likelihood of any drops remaining within and closing the passage 40 through any of the straws. When the compartments 20 are filled with the baskets 19, the double 45 boiler 8 with its paraffine content is lifted until the paraffine X totally surrounds the container 9 and the baskets 20 with the straws contained therein. To this end the double boiler 8 is provided with a hydraulic ram 21 which is lifted by water under pressure or other means under control of 45 the operator.

To accommodate the elevation and depression of the double boiler 8, the pipes 11 and 15 are connected with the supply and waste pipes 22 and 23 respectively through the folding pipe links 24 50 and 25 respectively. The scissors-like arrangement of these pipes provides a resilient connection between the pipes immediately connected with the double boiler and with the hot water supply with which the pipes 22 and 23 are con- 55

nected, said supply not being shown in the present drawings.

It will be understood that the heated water supplied by the jacket of the double boiler 8, 5 maintains the paraffine at an even temperature.

The container 9, after the compartments 20 have been filled, is closed by lowering the cover 16 and is locked in place by means of bolts 26 with which the said cover is provided. The cover 10 is in position when the double boiler 8 is raised. When the product having been saturated with paraffine, the boiler 8 is now lowered; the cover 15 substantially closes the upper opening of the double boiler 8 thereby retaining all of the heat of the paraffine and double boiler 8. The shaft 14 and the container 9 mounted thereon are now rapidly rotated by means of the power-driven mechanism having the belt 27 and electric motor 28. The rotation of the container 9 centrifugally 20 throws off all superfluous paraffine carried by the straws, or the container, to precipitate the same against the side walls of the double boiler 8. When the rotation has continued sufficiently long, the motor is stopped and the cover 16 is 25 lifted by means of the tackle employing the cables 29 which are attached to the cover by means of the eyelets. The wire baskets 19 are now lifted from the double boiler 8 to make way for a new supply. By expelling the paraffine from the 30 straws in the manner described all surplus is gotten rid of. The paraffine, at the time of its removal from the straw, is approximately as liquid as the paraffine in the bottom section of the boiler. This effect is due principally to the fact 35 that when the container 9 is freed from the liquid paraffine, it is held just above the liquid mass in the chamber formed by the cover 16, and the upper section 12 of the double boiler 8.

It is obvious that by means of this arrangement, the wringing process can be maintained to 40 absolute elimination from the product of any superfluous paraffine.

To support and guide the double boiler 8, and parts connected therewith, the standards 30 are 45 mounted on the standing structure and are so shaped as to form open runways or guides for the extension 31 connected to and set out from the boiler.

I claim:

50 1. A paraffining machine comprising a water jacketed boiler the jacketed portions whereof are separately supplied with heating material, means for elevating and depressing said boiler, a container adapted for holding the tubular product to be treated, said tubular product being disposed in radial disposition within said container, said container being supported by a stationary structure above said boiler in position to extend within the upper portion of said boiler when said 55 boiler is in its lowered position, a prime mover for rotating said container to cause the contents of said tubular product to be expelled therefrom horizontally, and a cover for said container to prevent the heat of said boiler from escaping 60 therefrom during the rotation of said container. 65

2. In a paraffining machine, a boiler for heating paraffine, a container for holding a product and to immerse the product in the paraffine within said boiler, said container providing a radial compartment having a greater dimension radially than circumferentially and entirely offset in one radial direction from the center whereby a product consisting of a number of tubes of greater length than the width of said compartment and positioned within said compartment will be maintained in substantially radial position, means for securing a relatively elevated position of the container above the level of the paraffine and means for rotating said container and centrifugally expelling the surplus paraffine from the tubes longitudinally of said tubes. 5 10 15

3. In a paraffining machine, a boiler for heating paraffine, a container for holding a product and to immerse the product in the paraffine within said boiler, said container providing a radial compartment having a greater dimension radially than circumferentially, a basket substantially fitting said compartment so as to likewise be positioned with a greater dimension radially than circumferentially and entirely offset in one radial direction from the center whereby a product consisting of a number of tubes of greater length than the width of said basket and positioned within said compartment will be maintained in substantially radial position, means for securing a relatively elevated position of the container above the level of the paraffine and means for rotating said container and centrifugally expelling the surplus paraffine from the tubes longitudinally of said tubes. 20 25 30 35

4. A paraffining machine having a boiler providing a lower paraffine-containing chamber and an upper centrifuging chamber, a rotatable container mounted within said boiler and including a plurality of spaced radial compartments entirely offset in one radial direction from the center for supporting segregated quantities of substantially radially-extending tubes, means for effecting relative vertical movement between said container and chambers, and means for rotating 40 45 said container within the centrifuging chamber to expel lengthwise of the tubes the surplus paraffine carried by the tubes.

5. A paraffining machine having a boiler providing a lower paraffine-containing chamber and 50 an upper centrifuging chamber, a rotatable member mounted within said boiler and having radially-disposed basket supports thereon in spaced relation, a plurality of independent baskets entirely offset in one radial direction from the center for containing tubes extending radially of said member, means for effecting relative vertical movement between said member and the chambers, and means for rotating said member within 55 60 the centrifuging chamber to expel lengthwise of the tubes contained in the baskets the surplus paraffine carried by the tubes.
